UNITED STATES PATENT OFFICE

KURT MORSBACH, OF BERLIN-LICHTERFELDE, GERMANY, ASSIGNOR, BY MESNE ASSIGNMENTS, TO PROJECTOR G. M. B. H., OF BERLIN, GERMANY, A CORPORATION OF GERMANY

FILM-STOPPING DEVICE

Application filed March 9, 1929, Serial No. 345,848, and in Germany January 4, 1927.

The present invention relates to a device for stopping the intermittent movement of the film through a film projecting apparatus by the use of which it is possible to suspend 5 the operation of the feeding mechanism of the film band at any movement as required, so that any particular film picture can be held stationary on the projection surface for the purpose of close examination.

One object of my invention is, by means of 10 a single releasing device on the one hand to draw back the gripping pins (which serve to move the film band intermittently through the gate) so far that they no longer extend 15 into the path of the film, and on the other hand simultaneously to cut out the driving mechanism, the film winding and unwinding mechanism, and also the feeding drum. The withdrawal of the gripping roller is effected 20 by a lever which moves the main shaft in an axial direction. This movement is rendered possible by the fact that, according to this invention, the drive is transferred from the main shaft to the feeding-roller and to the 25 film winding and unwinding mechanism by means of a worm.

Another feature of my invention is, that by means of this spiral screw the feeding and gripping devices are caused to return automatically once more to their working positions by the axial thrust of the worm, as soon as the releasing device, which serves to release the feeding and gripping devices, ceases to function.

A further feature of my invention is that simultaneously with the movement of the main shaft and the withdrawal of the gripping pins from the film band caused thereby, a coupling is disconnected by the action of a 40 second lever operated by the releasing device, which coupling is integral with the driving mechanism of the feeding-roller and the film winding and unwinding mechanism.

All these objects and features and certain 45 other features of my invention relating to the construction, combination and arrangement of parts will be more fully understood from the following detailed description of a typical form of the invention throughout

which description reference is had to the accompanying drawings, in which:

Fig. 1 is a longitudinal section of a projection apparatus with the stopping device that forms the subject of this invention. 55

Fig. 2 is the stopping device of Fig. 1 on a larger scale.

Fig. 3 is a view of the stopping device seen in the direction indicated by the arrow P of Fig. 2. 60

Fig. 4 is the stopping device in plan.

In these drawings, 1 is the housing of the projection apparatus, in the lower part 2 of which the film is lodged. The drive of the apparatus is effected either by a motor, not 65 shown in the drawings, which revolves the belt pulley 3 of the main shaft 4, or by means of a crank handle 5 which is fitted to the shaft 6 of the worm wheel 7, which latter cooperates with the spiral screw 8. The main 70 shaft 4 is adjustably housed on one side in supports 9 and on the other side in a socket 10 which is fitted to the front of the film channel 11. On the main shaft 4 are arranged one behind the other, a fly wheel 13 75 fitted with screening wings 12, a metal disc 14 which is bent in two planes, and an eccentric disc 15. By rotating the eccentric disc 15, a frame 16 is moved up and down, and in the lower part of this frame gripping 80 pins 17 are movably secured. The gripping pins 17 have at their ends a fork 18, in the slot of which engages the metal disc 14 which is bent in two planes, and by this means the gripping pins 17 are given a horizontal back- 85

ward and forward movement. The drive for the feeding drum 19 and the film winding and unwinding mechanism 20 passes from the spiral screw 8 over the worm wheel 7 to the worm wheel 21, which latter runs freely on the shaft 22. The latter carries at one end the feeding-roller 19, which is wedged tightly to it. The worm wheel 21 is provided with a pin 23, placed laterally, which, when coupled, engages in one of the holes 24 in the belt pulley 26 which serves to drive the belt 25 and thus the film winding and unwinding mechanism. The belt pulley 26 is fastened to spool 27. The latter is supplied with a slot 28 by means of which a pin 29 passes 95 100

through the shaft 22 housed inside the spool.

Between the pin 29 and the belt pulley 26 a spring 30 is placed around the outside of the spool 27, the function of which is to engage the coupling pin 23 in one of the holes 24 of the belt pulley 26. At the end of the spool 27 is a flange 31 against which rests a lever 32 which is rotatably fitted to the pivot 33. The end 32 of the lever protrudes through a slot 34 of the carrier plate 35. On the carrier plate 35 is movably fitted a push rod 36 in guides 37 in such a manner that its foremost end comes into contact with the end 32' of lever 32. At its side is the push rod 36, which is provided with a projection 38, against which one arm of a double armed lever 39 bent at right angles bears. The lever 39 is rotatably secured to the carrier plate 35 by means of a pivot 40. To the other arm of the lever 39 is joined a tension rod 41, which in its turn is connected with a vertical double-armed lever 42. The lever 42 is rotatable about the pivot 43, while its upper end 42' bears against flange 44, which latter is secured to the main driving shaft.

The mode of operation of the device is as follows:—

In normal working, i. e. when the stopping device is not functioning, by the rotation of the main shaft 4 on the one hand the gripping device is displaced to carry the film band through the gate, and on the other hand the feeding-roller 19 and the film winding and unwinding mechanism 20 are kept in continuous rotation. In this way the drive for the feeding drum 19 is transmitted through the spiral screw 8 on the worm wheel 7 and thence through the worm wheel 21 by means of the coupling pin 23 on the belt pulley 26. The belt pulley 26 drives the spool 27, and this in turn, by means of the pin 29, drives the shaft 22 of the feeding-roller 19. The drive for the film winding and unwinding mechanism is supplied by the belt pulley 26. As soon as the push rod 36 is pressed inwards, the gripping device, the feeding-roller and also the film winding and unwinding mechanism 20 are put out of the operation. By pressing the rod 36, the stop 38 is forced against the lever 39, so that the latter rotates about its pivot 40, and the upper part 42' of the lever 42 is thus pressed against the flange 44 of shaft 4, so that the latter is forced backwards. The shaft 4 takes the disc 14 with it, so that gripping pins 17 are drawn back so far that they can no longer engage in the film channel 11. Simultaneously with the action of the lever 42, the lever 32 is, by pushing rod 36 forwards, rotated about its pivot 33, in such manner that, in consequence of its pressure against the flange 31, the spool 27 and with it the belt pulley 26 act against the action of the spring 30 on the shaft 22, which movement is rendered easily possible by the formation of the slot 28. By this movement, the pin 23

is disengaged from the holes 24, so that the worm wheel 21 revolves freely on the shaft 22 and no longer takes with it the belt pulley 26 and the shaft 22. Thus in this manner the gripping device, the feeding drum 19, and the film winding and unwinding mechanism 20 are put out of operation. As soon as the pressure is released from the push rod, the gripping device and the film feeding mechanism once more come automatically into operation by means of the axial pressure of the spiral screw 8, of which the function is to move the shaft 4 back into its operative position. This effect of the axial thrust of the spiral screw 8 is strengthened by the spring 30. In spite of the sudden switching out of the gripping device and the film winding and unwinding mechanism, no acceleration in the speed of the motor occurs, as the fractional action of the levers 32 and 42, caused by the spiral pressure, against the flanges 31 and 34 is substantially equal to the force of the drive necessary for the mechanisms which have been put out of operation.

As can be seen from the preceding description, by the forward movement of the push rod 36 it is easily possible to put the gripping device and the feeding mechanism out of operation, while the rest of the mechanism continues in motion, so that any desired picture of the film band can be viewed as long as desired in a stationary position on the projection surface.

I claim:

1. In a film stopping device for stopping the intermittent movement of the film through a film projecting apparatus a push rod, an angle-lever one end of which engages a lateral projection of the push rod, a pivotally mounted lever one end of which is connected with the other end of the angle-lever by means of a tension rod, the other end of the pivotally mounted lever being pressed against a flange of the continuously rotating main shaft and axially shifting the same when the push rod is operated, gripping pins which are operated by the main shaft by means of a cam disc arranged thereon and which are retracted together with the driving shaft as to prevent them from engaging the film, and a spiral screw on the main shaft engaging a continuously rotating worm wheel which drives the feeding and the winding and unwinding mechanism by means of a coupling disconnected when the main shaft is axially shifted, the axial thrust of the spiral screw returning automatically the main shaft to its operative position when the push rod ceases to operate.

2. In a film stopping device for stopping the intermittent movement of the film through a film projecting apparatus a push rod, an angle-lever one end of which engages a lateral projection of the push rod, a pivotally mounted lever one end of which is con-

nected with the other end of the angle-lever by means of a tension rod, the other end of the pivotally mounted lever being pressed against a flange of the continuously rotating 5 main shaft and axially shifting the same when the push rod is operated, gripping pins which are operated by the main shaft by means of a cam disc arranged thereon and which are retracted together with the driving 10 shaft as to prevent them from engaging the film, a spiral screw on the main shaft engaging a continuously rotating worm wheel which drives the feeding and the winding and unwinding mechanism by means of a 15 coupling and a lever engaging the push rod and disconnecting the said coupling when the main shaft is axially shifted, the axial thrust of the spiral screw returning automatically the main shaft to its operative position when 20 the push rod ceases to operate.

3. In a film stopping device for stopping the intermittent movement of the film through a film projecting apparatus a push rod, an angle-lever one end of which engages a lateral projection of the push rod, a pivotally mounted lever one end of which is connected with the other end of the angle-lever by means of a tension rod, the other end of the pivotally mounted lever being pressed against 25 a flange of the continuously rotating main shaft and axially shifting the same when the push rod is operated, gripping pins which are operated by the main shaft by means of a cam disc arranged thereon and 30 which are retracted together with the driving shaft as to prevent them from engaging the film, a spiral screw on the main shaft engaging a continuously rotating worm wheel, a transmission worm wheel engaging the 35 other worm wheel and revolving freely on a spindle, a coupling pin placed laterally on the transmission worm wheel, a belt pulley provided with holes for the engagement of the coupling pin, a spring pressing the belt 40 pulley normally into engagement with the coupling pin of the transmission worm wheel, and a lever engaging the push rod and disconnecting the coupling of the transmission 45 worm wheel with the feeding and the winding and unwinding mechanism when the main shaft is axially shifted, the axial thrust of the spiral screw returning automatically the main shaft to its operative position when the 50 push rod ceases to operate.

4. In a film stopping device for stopping the intermittent movement of the film through a film projecting apparatus a push rod, an angle-lever one end of which engages a lateral projection of the push rod, a pivotally mounted lever one end of which is 55 connected with the other end of the angle-lever by means of tension rod, the other end of the pivotally mounted lever being pressed against a flange of the continuously rotating 60 main shaft and axially shifting the same

when the push rod is operated, gripping pins which are operated by the main shaft by means of a cam disc arranged thereon and which are retracted together with the driving shaft as to prevent them from engaging 70 the film, a spiral screw on the main shaft engaging a continuously rotating worm wheel, a transmission worm wheel engaging the other worm wheel and revolving freely on a spindle, a coupling pin placed laterally on the transmission worm wheel, a belt pulley provided with holes for the engagement of the coupling pin and fixed on a spool axially 75 slideable on the spindle and transmitting its rotation to the spindle, a spring pressing the belt pulley normally into engagement with the coupling pin of the transmission worm wheel, a feeding drum wedged tightly to the spindle, a film winding and unwinding mechanism driven by the belt pulley, and a lever 80 engaging the push rod and the spool, constraining the said spring and disconnecting thus the coupling pin and the belt pulley when the main shaft is axially shifted, the axial thrust of the spiral screw returning automatically 85 the main shaft to its operative position when the push rod ceases to operate.

5. A film feeding device for moving a film through a film projecting apparatus, comprising in combination, a continuously rotating and axially shiftable main shaft, gripping pins, a cam on the main shaft for operating said pins, means to yieldingly hold said pins in operative position, film feeding mechanism, coupling means for transferring driving action from the main shaft to the film feeding mechanism, means to yieldingly hold said coupling means in operative relation, and a releasing device simultaneously to shift axially the main shaft together with the cam 90 to thereby move said gripping pins from operative position, and to disconnect said coupling means.

6. A film feeding device for moving a film through a film projecting apparatus comprising in combination, a continuously rotating and axially shiftable main shaft, gripping pins, a cam on the main shaft for operating said pins, a spiral screw on the main shaft engaging a continuously rotating worm 100 wheel, film feeding mechanism, said worm wheel adapted to drive the film feeding mechanism through a coupling yieldingly held in operative relation, and a releasing device adapted simultaneously to axially shift the main shaft together with the cam thereon against the axial thrust of the spiral screw on the shaft to move the gripping pins from operative position, and to disconnect said coupling means.

In testimony whereof, I affix my signature.
KURT MORSBACH.
